[57] **CLAIM**

The ornamental design for a display column, as shown and described.

DESCRIPTION

FIG. 1 is a perspective view of a display column embodying my new design;

FIG. 2 is a side elevation view of FIG. 1;

FIG. 3 is a top plan view of the display column of FIG. 1; FIG. 4 is an enlarged fragmentary side elevation view of the circled portion 4—4 in FIG. 1 with the coins lined for the colors silver and copper, which are repeated randomly throughout the length of the display column, it being understood that the lining for color has been omitted in FIGS. 1 and 2 for convenience of illustration;

FIG. 5 is a perspective view of the display column with the coins omitted for clarity of illustration;

FIG. 6 is a side elevation view of FIG. 5; and,

FIG. 7 is a top plan view of FIG. 5.
